United States Patent Office

Des. 178,036

Patented June 19, 1956

178,036

ELECTRONIC DISPLAY CONSOLE

John H. Brown, San Diego, Calif., assignor to General Dynamics Corporation, a corporation of Delaware

Application December 28, 1955, Serial No. 39,505

Term of patent 14 years

(Cl. D26—5)

FIG. 1

I claim:

The ornamental design for an electronic display console, substantially as shown.
